UNITED STATES PATENT OFFICE.

JOHN COOPER, OF EVANSTON, ILLINOIS.

TOY RAILROAD TRACK.

Application filed March 26, 1926. Serial No. 97,718.

This invention relates to improvements in track systems of toy railroads, the general object of the invention being to provide a crossing whereby a train can pass from one track to a second track when going in either direction so as to make a toy track switch operate similar to the real railroad switches.

Another object of the invention is to make the crossing or switch compact so that the two tracks can be placed close together.

A further object of the invention is to provide simple means for operating the switch means.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a plan view of the improved crossing or switch.

Figure 2 is a bottom plan view thereof.

Figure 3 is a section on line 3-3 of Figure 1.

Figure 4 is a section on line 4-4 of Figure 1.

In these views, 1 indicates a base which is formed with the usual flanges 2 which are adapted to rest upon a floor or other support to hold the base spaced from said support. This base is adapted to be placed between portions of the track supporting means of the railroad at a point where the switch or crossing is desired to be located. The outer rail of track A is shown at 3 and the outer rail of track B is shown at 3', these rails being held to the base by the tongues 4 which are struck up from the base.

A pair of convergent rails 5 is carried by the base at each end thereof, the rails being slightly curved and abutting against a point 6 on the base. One of these rails 5 abuts the inner rail of the track A, while the other rail of each pair abuts the inner rail of the track B. A switch member C is placed at each end of the track portions A and B on the base and each member comprises the straight rail or tongue 7, the curved tongue or rail 8 and the base 9 to which the rails

are connected. Each member C is pivoted to the base intermediate its ends, as shown at 10. Triangular plates or points 11 are carried by the base, with their bases forming portions of the inner rails of the tracks A and B. These points 11 are adapted to be engaged by the inner ends of the members C. Each third rail 12 of the tracks A and B is formed with an enlarged portion 13 which is located over each member C and these enlarged portions of each track are connected by the depending parts 14 with a straight central part 15 which is insulated from the base, as shown at 16. Each depending part 14 passes under the curved tongue of each member C.

Four rotary disks 17, formed of insulating material, are carried by the central part of the base and each disk supports a rail section 18, the ends of which are beveled. Each disk is connected with the inner end of a member C by a link 19 so that the disk will be partly rotated by the movement of the member C.

A slightly conical disk 20 is carried by the central part of the base and is insulated from the base by the insulation 21 and said disk is electrically connected with one of the curved rails by means of the conductor 22. The rail sections are so arranged with respect to this disk that when they are moved to a certain position, their inner ends will contact with the disk and thus they will receive a portion of the current passing through the third rail. By making the disk with a sloping upper face, contact is insured between the disk and rail sections.

The base is provided with a pair of extensions 1' at one side thereof, an extension being arranged adjacent each end of the base and each extension supports a switch operating member which comprises a disk 23 rotatably supported and having a handle 24 thereon by which it can be moved and this disk is connected by a link 25 with the switch member C nearest to it. A link 26 connects the link 25 with a lever 27 which is pivoted at its center to the center of the base, as shown at 28, the pivotal point being below the center of the disk 20 and the other end of said lever 27 is connected by a link 29 with the switch member C of the other track and at the far end of the base.

From the foregoing it will be seen that when the switch operating means at the right hand side of the device is operated, the link

25 will rock the member C at the right hand end of track B until its curved rail strikes the point 11, and this movement will rock the lever 27 and cause it, through means 5 of the link 29, to shift the member C at the far end of track A in a similar manner so that it will engage the other point 11. A pair of track sections 18 will bridge the points 11 and 6, while the other pair of 10 track sections will have been moved by the movement of the members C as just explained into a position where they will align with each other and will be located at the center of the track formed by the other sections 15 and thus form part of the third rail. It will be noted that the inner ends of the aligned sections will engage the disk 20 so that they will receive current therefrom. In this position of the parts, a train can pass 20 from track B on to track A and vice versa, the wheels of the train passing along the curved rail 8 of section B and one of the rails 5 across the rail forming sections 18, the points 6 and 11 on to the curved tongue 25 of the other member C and the other rail 5. By turning the lever 24 in an opposite direction, the switch members at the right of track B and the left of track A will be moved to a position similar to that occupied by the 30 other switch members so that a train can pass over each track without leaving the same. Then by operating the other switch actuating means, the switch members C at the left of track B and the right of track A 35 will be moved to a position where a train moving to the right can pass from track B on to track A or a train moving to the left on track A can pass to track B.

It will thus be seen that I have provided 40 an eight way crossing which is very compact and which permits the two tracks to be placed close together. Two of the track sections 18 will serve as wheel engaging members, while the other two serve as conductors. 45 This invention makes the toy railroad similar to the real railroads. The switches are easily operated.

It is thought from the foregoing description that the advantages and novel features 50 of my invention will be readily apparent.

I desire it to be understood that I may make changes in the construction and in the combination and arrangement of the several parts, provided that such changes fall within 55 in the scope of the appended claims.

What I claim is:—

1. In a double track toy railway, a section comprising a support, outer rails of the two tracks thereon, a pair of converging rails at 60 each end of the support, said converging rails forming the inner rails of the two tracks, switch members pivotally connected with the support and arranged at the ends of the track sections, each member comprising a base, a straight rail and a curved rail,

four rotary disks in the support, means for rotating the disks by the movement of the switch members, a short rail section carried by each disk, a pair of stationary points on the support, the space between which and the inner ends of the converging rails is 70 bridged by two of the rail sections, means for supplying current to the other rail sections which form portions of the third rail and manually operated means for adjusting 75 the switch members.

2. In a double track toy railroad, a track section comprising a base, outer rails of the two tracks carried thereby, a pair of converging rails at each end of the base forming the inner rails of the tracks, a point on the base at the inner end of each pair of convergent rails, a third rail for each track on the section, each third rail having a pair of flattened portions, switch members pivotally supported on the base, one at each end of each track, each member comprising a base, a straight rail and a curved rail, four rotary disks carried by the base, a link connecting each disk with a switch member so 80 that the rocking movement of the member will partially rotate the disk, a central disk, means for connecting the same with one of the third rails, a rail section carried by each disk, a pair of triangular members on the 85 base, the bases of which form portions of the inner rails of the tracks, two of the rail sections bridging the spaces between the triangular plates and the points of the convergent rails while the other two are in alignment 90 and contact with the center disk to form part of a third rail, a pair of manually operated members, a link connecting each member to the switch member which is 95 closest to it, a pair of rocking levers pivotally supported at their centers and links 100 connecting each lever with a pair of switch members which are diagonally opposite each other.

3. A track section for a double track toy 110 railway comprising a base, a pair of tracks thereon, each track comprising a straight outer rail and a pair of curved inner rails, each inner rail converging to a point with an inner rail of the other track, stationary 115 members on the base having portions forming parts of the inner rails, four rail sections, two bridging the spaces between the inner ends of the curved rails and the stationary members, while the other pair align 120 themselves between the other two and form parts of the conducting means, a pivoted switch member at each end of each track, each member including an outer rail and an inner rail, means for actuating the switch 125 members and means for moving the rail sections by the movement of the switch members.

In testimony whereof I affix my signature.
JOHN COOPER.
